HONE FOR DOUBLE-EDGED RAZOR BLADES

Filed Jan. 26, 1946

UNITED STATES PATENT OFFICE

2,467,650

HONE FOR DOUBLE-EDGED RAZOR BLADES

Harry G. Ashworth, Salamanca, N. Y.

Application January 26, 1946, Serial No. 643,557

4 Claims. (Cl. 51—151)

1

This invention relates to a hone for double edged safety razor blades, and more particularly to such a hone in which the two edges of the razor blade are stropped between surfaces of soft leather, cork or the like so as to remove the microscopic burrs or barbs on the cutting edges and thereby improve the cutting qualities of the blade.

The principal object of the present invention is to provide a simple hone having two pairs of mating surfaces of soft leather, cork or the like and between which the razor blade is moved lengthwise of its cutting edges so that the action of the stropping surfaces is lengthwise of these edges. With strops which work transversely of the cutting edge of a razor blade the effect is to attenuate the microscopic burrs or barbs of the cutting edge with very little improvement of the cutting quality of the razor edge. I have found that by moving each edge lengthwise between a pair of mating soft leather or cork surfaces these microscopic burrs or barbs are removed, instead of being merely attenuated, and greatly improve the cutting qualities of both new razor blades and also razor blades which have undergone repeated use.

A further object of the invention is to provide such a strop in which the razor blade can readily be inserted and in which the means for effecting movement of the blade relative to the stropping surface is a simple operation. By this means the razor blade can be quickly honed with little effort.

Another object of the invention is to provide a hone which operates simultaneously on the opposite parallel cutting edges of a double edged razor blade.

Another aim is to provide such a razor blade holder in which the honing pressure can readily be varied by varying the degree of tightness with which the hone is held.

Another aim of the invention is to provide a hone which comprises but three moving parts which can be readily stamped from stainless steel or any other metal or can be readily formed from plastics.

Another object of the invention is to provide such a hone which is extremely compact and can readily be placed in a bathroom cabinet, traveling case or the like.

Other objects are to provide such a hone which is attractive in appearance and of strong durable construction so as to stand up under conditions of severe and constant use.

In the accompanying drawings:

Fig. 1 is a perspective view of a hone embody-

2

ing the present invention and showing the same opened to permit of insertion or removal of a razor blade, the razor blade being indicated in phantom.

5 Fig. 2 is a vertical, central, longitudinal section through the hone.

Fig. 3 is a horizontal sectional view taken on line 3—3, Fig. 2.

Fig. 4 is a vertical transverse section taken on line 4—4, Fig. 2.

10 The body of the hone is shown as being composed of two body members indicated generally at 5 and 6 which are pivoted together at one end of the hone, as indicated at 8, so that the body is capable of being opened up, as shown in Fig. 1. The lower body member 5 is of elongated dished form having a flat bottom 7, upstanding longitudinal side walls 9, a rear end wall 10 and a front end wall 11. The upper body member 6 is of elongated channel shaped form having a flat top wall 12, longitudinal extending side walls 13 and a front wall 14. The side walls 13 of the top body member 6 are spaced to embrace and fit the side walls 9 of the lower body member 5 and the front wall 14 is shaped to embrace and fit over the front wall 11 of the lower body member 5. At the rear end of the strop the two body members 5 and 6 are connected by the pivot pin indicated at 8, this pin being in the form of an elongated headed rivet extending horizontally through the side walls 9 and 11 of the body sections 5 and 6. A metal channel 15 is arranged centrally in the upper body member 6 and has its legs secured to the top thereof, this channel

15 30 35 40 45

extending the full length of the upper body member 6 so as to provide two longitudinal channels 16 on opposite sides thereof. Similarly, a metal channel 18 is arranged centrally in the lower body member 5 and extends longitudinally the full length thereof to provide a pair of channels 19 on opposite sides thereof. Within each channel 16 is fitted a strip 20 of relatively soft stropping material, such as leather or cork, and a similar strip 21 is arranged in each of the channels 19. To provide an additional resilience, each of these strips 20, 21 can be backed by a strip 22 of rubber or other highly resilient material.

It will be seen that the faces of each pair of the leather or cork strips 20, 21 oppose each other and these opposing faces are preferably arranged in slightly divergent relation to each other to conform to the cutting edge of the razor blade 25 arranged therebetween.

This razor blade 25 is placed lengthwise of the stropper with its cutting edges between the

opposing faces of the leather or cork strips 20, 21 and is moved lengthwise so that the microscopic burrs or barbs on these edges are removed instead of being attenuated as is the case where a razor blade is stropped transversely of its cutting edge. For this purpose the channel 18 of the lower body member 5 is provided with a longitudinal slot 26 in its upper face and within this lower channel 18 is arranged a metal slide 29. This slide has a handle 36 which projects out through a slot 31 provided in the front wall 11 of the lower body member 5. This slide is also formed to provide a plurality of downwardly extending rounded lugs 32 which ride on the bottom wall 7 of the lower body member 5 and support the slide 29 to move parallel with this bottom 7 as it is worked back and forth longitudinally of the strop. These lugs 32 are shown as being four in number and as being formed by offsetting the metal of the slide 29.

The slide 29 is also formed to provide a pair of integral pins or teats 33 which project upwardly through the slot 26 in the channel 18. These pins 33 are formed by off-setting the metal of the slide 29 and are of precise shape and spacing to fit the holes or irregularly shaped central slot 35 provided in the usual double edged razor blade.

It will be seen that the use of the strop forming the subject of the invention is very simple. Thus the user swings open the body members 5 and 6 about the pivot 8 and places the razor blade 25 so that its central slot 35 fits the pins 33 which project upwardly from the slide 29. When so fitted the edges of the razor blade are arranged parallel with the longitudinal dimension of the strop. The user then closes the body members 5, 6 and works the handle back and forth. In closing the body members the strips 20, 21 of leather or cork are brought into engagement with the opposite sides of the cutting edges of the blade and the pressure exerted by these leather or cork strips 20, 21 in stropping the blade can be regulated by the degree of tightness with which the user holds the body members 5, 6 together. These strips 20, 21 resiliently engage the blade, both through their inherent resilience and also because of the rubber backings 22 for these strips. In working the handle 20 back and forth the slide 29 is moved longitudinally of the strop, this slide riding on its lugs 32. Since the pins 33 project upwardly through the slot 26 in the channel 18 which encloses the slide, and since these pins fit the central slot of the razor blade, the razor blade 25 is moved longitudinally and its cutting edges are therefore stropped, longitudinally, by the leather or cork strips 20, 21. This longitudinal stropping of the edges of the razor blade has been found to be remarkably effective in removing the microscopic barbs or burrs thereon, particularly in contrast with transverse stropping where these barbs or burrs are merely attenuated.

From the foregoing it will be seen that the present invention provides a very compact, low cost razor blade strop which maintains a cutting edge of high quality on each side of a double edged blade, particularly in that the stropping is effected lengthwise of these edges, and it will further be seen that the strop is very easily manipulated to rapidly bring the edges of the razor blade into proper condition.

I claim as my invention:

1. A hone for double edged razor blades, comprising an elongated holder section, a comple-

mentary elongated holder section separable from said first holder section, one of said holder sections being channel-shaped in cross section to form a channel-shaped holder section, an elongated channel-shaped member secured longitudinally and centrally within said channel-shaped holder section with the edges of its flanges in engagement with said channel-shaped holder section to form a covered slideway and forming a pair of longitudinal channels on opposite sides thereof, a pair of elongated strips of soft, resilient honing material fitted in each of said channels, a strip of soft, resilient honing material secured along the opposite sides of the other holder section and mating with said first pair of honing strips when said holder sections are brought together, said blade being insertable between said holder sections with its opposite edges between said opposed pairs of honing strips, a slide fitted in said slideway and projecting longitudinally outwardly from one end of said holder for manual reciprocation thereof, and a projection on said slide and extending through a longitudinal slot in said channel-shaped member and fitting said blade, whereby the blade fitted thereon is reciprocated lengthwise of its cutting edges by said slide and said blade is honed lengthwise of its cutting edges.

2. A hone for double edged razor blades, comprising an elongated holder section which is channel-shaped in cross section to form a channel-shaped holder section, a complementary elongated holder section which is channel-shaped in cross section to form a channel-shaped holder section, a pair of elongated channel-shaped members each secured longitudinally and centrally in a corresponding one of said channel-shaped holder sections with the edges of its flanges in engagement therewith and providing channels on opposite sides of each of said holder sections one side of each of which channels is formed by the corresponding side flange of the corresponding holder section, an elongated strip of soft, resilient honing material fitted in each of said channels with the pairs of honing strips on opposite sides of said holder in mating engagement with each other, said blade being insertable between said holder sections with its opposite edges between said mating pairs of honing strips, a slide fitted longitudinally in one of said channel-shaped members and projecting longitudinally outwardly from one end of said holder for manual reciprocation thereof, and a projection on said slide and extending through a longitudinal slot in said one of said channel-shaped members and fitting said blade, whereby the blade fitted thereon is reciprocated lengthwise of its cutting edges by said slide and said blade is honed lengthwise of its cutting edges.

3. A hone for double edged razor blades, comprising an elongated holder section, a complementary elongated holder section separable from said first holder section, one of said holder sections being channel-shaped in cross section to form a channel-shaped holder section, an elongated channel-shaped member secured longitudinally and centrally within said channel-shaped holder section with the edges of its flanges in engagement with said channel-shaped holder section to form a covered slideway and forming a pair of longitudinal channels on opposite sides thereof, a pair of elongated strips of soft, resilient honing material fitted in each of said channels, a strip of soft, resilient honing material secured along each of the opposite sides

of the other holder section and mating with said first pair of honing strips when said holder sections are brought together, said blade being insertable between said holder sections with its opposite edges between said opposed pairs of honing strips, a slide fitted in said slideway and projecting longitudinally outwardly from one end of said channel-shaped holder section for manual reciprocation thereof, a projection on said slide and extending through a longitudinal slot in said channel-shaped member and fitting said blade, whereby the blade fitted thereon is reciprocated lengthwise of its cutting edges by said slide and said blade is honed lengthwise of its cutting edges, and a plurality of lugs pressed outwardly from said slide toward the opposing face of said channel-shaped holder and having sliding engagement therewith.

4. A hone for double edged razor blades, comprising an elongated holder section which is channel-shaped in cross section, a complementary elongated holder section which is channel-shaped in cross section with its side flanges embracing the side flanges of said first holder section, a pivot pin extending through said side flanges of both holder sections at one end of the hone and permitting the pivotal separation of said holder sections, an elongated central member secured centrally within each of said holder sections parallel with said side flanges and each forming with the said side flanges of its holder section a pair of longitudinal channels on opposite sides thereof, a honing strip of soft, resilient honing material secured in each of said channels and each mating and engaging with a corresponding honing strip in the opposing

channel of the other holder section when said holder sections are swung together about said pivot pin, one of said elongated central members being formed to provide a slideway opening through the end of the corresponding holder section opposite said pivot pin, a slide fitted longitudinally in said slideway and having a handle portion projecting outwardly therefrom, means retaining said slide in said slideway when said sections are separated from each other, and a projection on said slide and fitting a blade between said holder sections with its opposite edges between said opposed pairs of honing strips whereby the blade fitted thereon can be reciprocated lengthwise of its cutting edges by said slide.
